A. NOBLE

PROCESS FOR THE PRODUCTION OF PHOSPHORIC ACID

Filed Feb. 29, 1924

UNITED STATES PATENT OFFICE.

ALBERT NOBLE, OF ANNISTON, ALABAMA, ASSIGNOR TO FEDERAL PHOSPHORUS COMPANY, OF BIRMINGHAM, ALABAMA, A CORPORATION OF ALABAMA.

PROCESS FOR THE PRODUCTION OF PHOSPHORIC ACID.

Application filed February 29, 1924. Serial No. 695,945.

This invention relates to the smelting of phosphatic material and more particularly, but not exclusively, to the manufacture of phosphoric acid; and comprises a method 5 wherein a charge composed, for example, of phosphate rock, carbon, and silica or a silicate, is heated by the combustion of powdered coal, fuel oil, natural or producer gas, at sufficient temperature to cause the phosphorus to be eliminated from the molten slag and subsequently oxidized and collected, the heat from the oxidation of the gases being utilized to preheat the air for combustion and oxidation.

15 The object of this invention is to provide for the treatment in fuel heated furnaces of phosphatic material and especially low grade phosphate rock whereby phosphoric acid may be economically produced, in a 20 manner not heretofore possible.

In order that my invention may be fully understood, and clearly differentiated from the prior art, the following description is given, whereby those skilled in the art may 25 practice my invention.

I propose to combine with a hearth upon which the charge is smelted an overhead stack of substantially less width than the hearth, through which the charge descends 30 to the hearth and is there subjected on one side to the action of an impinging flame or flames which smelt it, causing its evolved gases to pass from the other side of the charge to a combustion chamber to which 35 air is admitted by which they are completely oxidized, the air being preferably caused to flow down the stack through the charge. It is an important step in my invention that the intense heat of oxidation of 40 the evolved gases is largely saved and economically utilized by its transfer to the air supplied to the furnace for the purposes of combustion or oxidation or both, but especially for oxidation as this air can be 45 caused to flow slowly down through the descending charge in the stack in such manner as to transfer its heat to the charge in the most efficient manner and to preheat the latter and thus proportionately reduce the 50 fuel required to smelt it. Obviously, the preheating of the air of combustion will also conserve fuel and increase the temperature of the impinging flames.

My invention contemplates the employ-

ment of a flame or flames in the heating chamber at one side of the hearth which play over the stock pile resting on the hearth, impinging against it and flowing freely over its spreading base towards the combustion or oxidizing chamber at the other side of the hearth, causing the principal fusion zone to extend about the side of the stock pile adjacent to the flame. This results in sealing with the fusing stock the pile against the deep penetration of the flames. A surface smelting, therefore, results from the impinging and enveloping flame principally on one side and the smelting stock seals that side so that air of oxidation flowing down through the stack will pass out therefrom through the stock only on the side towards the combustion chamber. In this way I maintain the reducing atmosphere desirable in the heating chamber and supply the necessary air in the most effective way to the 75 oxidizing chamber. This gives a free flow of air through the charge in the feeding stack and permits its uniform escape into the oxidizing compartment. Moreover the down-flow of air through the stock causes the dust 80 to be filtered out of it, as the smaller particles melt quicker than the larger pieces of stock and will adhere to the latter and thus will not tend to become entrained with the air.

I have found that it is an advantage to have the preheated air enter the furnace along with and in the same direction as the descending stock, as I thereby avoid the tendency of the charge to "scaffold" or adhere to the side walls of the feed stack. If the evolved gases pass up through the feed stack, these highly heated gases, given sufficient air for combustion, will sinter the charge and cause it to stick to the side walls 95 of the stack. I have also found that by burning the evolved gases near the surface of the charge on the hearth, there is an improvement in the smelting efficiency in that the heat is reflected to the surface of the 100 melting charge.

If it is desirable to do so, feldspar, shale, or other potash bearing silicates may be used as a substitute for sand. In such cases, the potash is driven off and may be collected along with the phosphoric acid fume. The silica of combustion in the silicate reacts with the lime in the phosphate rock and is

removed from the furnace in a manner similar to that for tapping slag, when sand is used as an acid flux.

In the practice of my invention I make intimate mixture of phosphate rock, silica and coke according to the following chemical equation:

10 The mixture is based on chemical analysis of the component materials. Additional coke is added to the mixture, equivalent to approximately 15% in excess of that necessary for the above equation, because it has 15 been found that a certain portion is always burned away by the air and some is carried off entrained in the gases; hence the necessity for additional coke.

As illustrative of a typical apparatus embodying the essential elements for carrying out in the preferred manner the operation of my process, reference is made to the following drawing, in which:—

20 A feed stack 1, superimposed on a heating chamber 2, is shown, having burners 3 and a tap hole 4. The mixture of phosphatic material, coke and silica is introduced through a charging door 5, fills the feed stack 1 and rests on a hearth 6, where 25 the flame from burners 3 plays on it. Pre-heated air is introduced through an inlet 7, and after passing downward with the stock, combines with the evolved phosphorus and carbon monoxide at the surface 30 of the stock 8. The products of combustion from the fuel burners and evolved gases commingle in the chamber 9 and pass 35 out into a heat interchange 10 which is conventionally illustrated. Air is drawn 40 through ports 11, and after passing through the heat interchange, is forced by a fan 12 into the feed stack 1. After the heat has 45 been absorbed from the phosphoric acid bearing gases, they are drawn away by a fan 50 13 and forced into the header of an electrical precipitator 14 which comprises pipes 15, insulated wires 16, a source of current 17, a ground connection 18, and an acid receiving basin 19.

55 I prefer conducting my process in this apparatus in the following manner:—

A normal charging mixture may consist of 1500 lbs. phosphate rock, analyzing 15% phosphorus, 350 lbs. sand and 357 lbs. coke, including the excess required to make up losses. There will be variations from these proportions, depending on the analysis of the component materials. This mixture is introduced through the charging door 5 until the charge fills up that portion of the feed stack connecting with the heating chamber 2. The burners are then ignited and the flame impinges on one side of the stock resting on the hearth 6. Then the fans 12 and 13 are started. After these fans

have been in operation a short time, the heat begins to decompose the phosphatic material, principally on the burner side of the stock pile 8 when phosphorus fume and carbon monoxide will be evolved. These 70 gases are burned principally at the surface of the other side of the stock pile 8 and supply heat through the interchanger to raise the temperature of the combustion of the evolved gases. When the gases are being evolved at a uniform rate the feed stack is filled to air inlet 7. As the slag collects on the hearth it is kept in a molten condition by the flame impinging on and enveloping or encircling the stock on the hearth 6, so that periodically this slag may be tapped as is practiced in any slagging furnace operation. The phosphoric acid produced may be collected in the electrical precipitator as shown, or in any satisfactory collecting equipment as an absorption tower or condenser.

75 Though I have described with great particularity the details of the embodiment of the invention herein shown, it is not to be construed that I am limited thereto, as changes in arrangement and substitution of equivalents may be made by those skilled in the art without departing from the invention as defined in the appended claims.

80 I do not claim herein the apparatus, as this application, because of divisional requirements, is limited to the process hereinbefore described.

85 Having thus described my invention, what I claim as new and desire to secure by Letters Patent, is:—

90 1. A process for the manufacture of phosphoric acid, which consists in charging a mixture of phosphate rock, silica and carbon into a feed stack disposed over the hearth of a heating chamber, impinging a flame on the charge in the heating chamber, passing air downwardly through the feed stack, oxidizing the evolved gases during 95 their sojourn in the heating chamber, transferring heat from the gases to preheat air for combustion of the fuel, and collecting the oxidized phosphorus compounds.

100 2. A process for the manufacture of phosphoric acid, which consists in charging a mixture of phosphate rock, silica and carbon into a feed stack disposed over the hearth of a heating chamber, impinging a flame on the charge in the heating chamber, passing air downwardly through the feed stack, oxidizing the evolved gases during 105 their sojourn in the heating chamber, transferring heat from the gases to preheat air for combustion of the fuel and for the oxidation of the gases, and collecting the oxidized phosphorus compounds.

110 3. A process for the manufacture of phosphoric acid, which consists in charging a mixture of phosphate rock, silica and car-

bon into a feed stack disposed over the hearth of a heating chamber, impinging a flame on one side only of the charge in the heating chamber, passing air downwardly 5 through the feed stack, oxidizing the evolved gases during their sojourn in the heating chamber, transferring heat from the gases to preheat air for combustion of the fuel, and collecting the oxidized phosphorus compounds.

4. A process for the manufacture of phosphoric acid, which consists in charging a mixture of phosphate rock, silica and carbon through a feed stack onto a hearth, impinging a flame on the surface of the charge 15 on the hearth, passing preheated air down-

wardly through the column of charge in the same direction as the passage of the stock, then oxidizing the evolving gases outside of the feed stack, and collecting the oxidized phosphorus compounds.

5. A process for the manufacture of phosphoric acid, which consists in charging a mixture of phosphate rock, silica and carbon through a feed stack onto a hearth, impinging a flame on one side of the surface of the charge resting on the hearth, admitting air to the gases on the other side of the charge for oxidation, and collecting the oxidized phosphorus compounds.

In testimony whereof I affix my signature.
ALBERT NOBLE.
